UNITED STATES PATENT OFFICE.

JOSEPH J. HOTCHKISS, OF RALEIGH, NORTH CAROLINA.

MEASURING-PUMP.

1,117,052.

Specification of Letters Patent. Patented Nov. 10, 1914.

Application filed September 23, 1913. Serial No. 791,363.

To all whom it may concern:

Be it known that I, JOSEPH J. HOTCHKISS, a citizen of the United States, residing at Raleigh, in the county of Wake and State of North Carolina, have invented a new and useful Measuring-Pump, of which the following is a specification.

This invention relates to improvements in measuring pumps.

10 An object of the present invention is to provide a measuring pump including a cylinder with piston reciprocatingly mounted therein, and above which is positioned a rack bar and a gear segment for the actuation thereof.

15 A still further object of the invention is to provide a rotatable drum with stops positioned upon the outer periphery thereof and helically arranged therearound and 20 with means whereby the said drum may be rotated to bring the said stops into the path of movement of parts connected with the piston, and to further provide the said drum with a plurality of notches and a 25 pawl engageable therewith so that the drum will be brought to a sudden stop as each projection or stop of the drum rotates into the path of movement of the rack bar.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed can be made within the scope of what is claimed without departing from the spirit of the invention.

40 In the drawings accompanying this specification and forming a part thereof, the preferable form of my invention is illustrated, in which—

Figure 1 is a view in elevation of my 45 improved measuring pump, parts thereof being broken away to more clearly illustrate the internal constructions thereof. Fig. 2 is a top plan view of parts of the measuring pump and including the means 50 of support for the rotatable drum. Fig. 3 is a sectional view taken through the top of the drum. Fig. 4 is a fragmentary view of the bottom portion of the drum. Fig. 5 is a fragmentary view in perspective of 55 a portion of the rack bar and illustrating the arm-like projection which extends

therefrom. Fig. 6 is a fragmental view in section through the lower part of the drum. The segment 20 is rotated out of contact with the rack bar allowing the latter to move forward with the result that the teeth of the rack bar are engaging the front extremity of the slot through which the rack bar slides.

Referring to the drawings in which similar reference numerals indicate corresponding parts of the several views, the wall plate 7 is provided with an outwardly extending shelf 8 and upon which is mounted the mechanism of my improved measuring pump.

The cylinder 9 is provided with a tapering portion 10 and in which are mounted the ball valves 11 and 12 of different diameters and which act in the capacity of 75 checks for the liquid after it has passed into the cylinder through the inlet pipe 13. An outlet flap valve 14 is provided allowing the liquid to pass out through the outlet pipe 15 as the piston 16 is driven 80 downwardly in the cylinder and maintaining a vacuum within the cylinder upon the up-stroke of the said piston.

The above construction is such that a reciprocation of the piston within the cylinder 85 9 raises the liquid through the inlet pipe 13 past the ball check valves 11 and 12 and through the apertured plate 17 and into the body of the cylinder. A down-stroke of the piston forces the liquid out through the flap valve 14 and to the delivering or outlet pipe 15, below which a receptacle may be positioned. The area of the piston remaining constant, the amount of liquid delivered by the pump during each 90 reciprocation or complete stroke of the piston depends upon, and is functional of the length of the stroke of the piston.

A piston rod 18 extends upwardly from the piston 16 and is provided with a rack 100 bar 19 at the upper end thereof and meshes with a gear 20, which latter is provided with a handle 21 extending therefrom whereby the gear may be rotated which will result in the reciprocation of the piston.

The stroke controlling drum 22 is rotatably mounted adjacent the rack bar 19 at its lower extremity by the outwardly extending bracket 23 and at its upper extremity by the curved bell crank shaped 110 bracket 24. The brackets 23 and 24 are each provided with the arms 25 which are

provided with suitable slots 26 therein and through which extends the rack bar 19 which is for rectilinear reciprocation thereby. It will be noted from reference to Figs. 2 and 6, that the slots 26 are of sufficient size to accommodate the said rack bar and allow the teeth to pass therethrough without interference therefrom. It being noted that the gear 20 which is in constant mesh with the rack bar forces the smooth portion of the rack bar against the side walls of the slots and prevents the teeth from coming in contact therewith which would tend to lock the piston against reciprocation. In this connection however, it is to be noted that the segmental gear 20 is of such a size that it can rotate to such a point that the teeth thereof can be rotated out of mesh with the teeth of the rack bar, in which instance, the rack bar, due to the resiliency of the piston rod 18 will move forwardly against the front of the slot with the result that the teeth lock therewith and hold the piston in the position assumed when disconnected from the segmental gear, also allowing for the complete removing thereof from the cylinder be it so desired.

The stroke controlling rotatable drum 22 is provided at its upper and lower extremities with overhanging bases 27 and 28. A plurality of stops 29 are rigidly secured to the outer surface of the drum and offset one with respect to the other in both a horizontal and vertical manner so as to wind helically thereabout.

As illustrated in Fig. 5, the rack bar 19 is provided with the projecting arms 30 extending therefrom and the path of movement of which is intersected by the successive stops 29 and the overhanging base 27, so that the length of stroke of the rack bar 19 is limited in a downward direction by one of the stops 29 which happens to be in the path of movement thereof. The stop 30 is of limited dimensions and does not strike the overhanging base 27 during the removal of the piston, it being noted that the segmental gear 20 is rotated out of contact with the rack bar during such procedure which allows the entire rack bar to move forward as previously explained.

A handle 31 is rigidly secured to the drum 22 through the trunnions 32 whereby the drum may be rotated by an actuation of the handle 31 to bring the desired stop in the path of movement of the projecting arm 30 and thus limit the stroke of the piston to the desired amount. The lower overhanging base 28 is provided with a plurality of notches 33 therein and coating with which is the spring pawl 34 which is adapted to resiliently seat in the said notches and hold the drum against accidental rotation. Thus as the handle 31 is actuated, the drum will

be rotated, unseating the pawl from one of the notches until the pawl comes into registration with some other notch into which it immediately springs and greatly increases the pressure necessary for further rotation of the drum, automatically informing the operator that one of the lugs has been properly positioned within the path of movement of the offset arm 30 and will properly limit the downward motion thereof. An indicator is marked upon the surface of the drum opposite each of the stops 29 and which stops are so spaced that a standard quantity or volume of liquid will be expelled from the piston when the rack bar's projecting arm is reciprocated between the overhanging base 27 and one of the various stops. It is to be noted that the stops do not extend entirely around the stroke controlling drum so that the said drum may be brought into a position whereby the free reciprocation of the piston may take place when it is desired to pump a considerable quantity of liquid and when it is not desired to exactly measure the amount of liquid so delivered.

Having thus fully described my invention what I claim as new is—

1. In a measuring pump, the combination of a pump portion, a piston rod extending therefrom, means for reciprocating said piston rod, an arm projecting from said piston rod and carried thereby, a rotatable drum mounted adjacent the said piston rod, the said drum provided with overhanging bases, one of said bases adapted to limit the movement of said piston rod in one direction, a plurality of helically arranged stops projecting from the surface of said drum and adapted to limit the reciprocation of said piston rod in the opposite direction, a manually operable handle secured to said drum and adapted to rotate the same, one of said bases of the drum provided with a plurality of notches therein, and a spring controlled pawl resiliently seating within the said notches, the said pawl and notches coacting to hold one of the stops of the drum in the line of movement of the piston rod arm.

2. A device of the class described including a pump comprising a resilient piston rod, a rack bar carried by said piston rod, a segmental gear meshing with said rack bar and adapted to rotate out of contact therewith, brackets provided with slots therein for the reception and guidance of said rack bar, said rack bar held against the rear portions of said slots by said segmental gear when in contact therewith, the said rack bar adapted by the resiliency of the piston rod to move into contact with the forward portions of said slots when the said segmental gear is rotated out of mesh therewith.

3. An apparatus of the class described comprising a pump having a resilient piston

rod, a rack bar carried by the piston rod thereof, a segmental gear meshing with said rack bar and adapted to rotate out of contact therewith, means for slidably mounting said rack bar, said rack bar adapted to be forced forwardly into interlocking engagement with the said means whereby the rack bar is slidably mounted owing to the resiliency of said piston rod, when the said seg-

mental gear is rotated out of engagement to therewith.

In testimony that I claim the foregoing as my own, I have hereto affixed my signature in the presence of two witnesses.
